UNITED STATES PATENT OFFICE.

MINOR EUGENE TYNES, OF GLOSTER, MISSISSIPPI.

POULTRY-SHIPPING COOP.

1,069,743.

Specification of Letters Patent. Patented Aug. 12, 1913.

Application filed June 5, 1912. Serial No. 701,860.

To all whom it may concern:

Be it known that I, MINOR E. TYNES, a citizen of the United States, residing at Gloster, in the county of Amite and State 5 of Mississippi, have invented a new and useful Poultry-Shipping Coop, of which the following is a specification.

One object of the present invention is to provide a coop for shipping poultry, so 10 constructed that it may be collapsed readily, to occupy small space when not in use and upon the return transit.

A further object of the invention is to provide novel means for maintaining the 15 coop in expanded condition.

The invention aims further to provide a coop the netting of which is so positioned that frequent folding of the netting will not stiffen and break the same.

20 A further object of the invention is to improve generally, devices of that type to which the present invention appertains.

In the drawings,—Figure 1 is a top plan; Fig. 2 is a section on the line 2—2 of Fig. 25 1; Fig. 3 is an end elevation; Fig. 4 is a side elevation, showing the coop collapsed; Fig. 5 is a longitudinal section of the coop, the same being in collapsed condition; Fig. 6 is a transverse section, the coop being 30 collapsed, as shown in Figs. 4 and 5; Fig. 7 is an elevational detail showing the co-operation between one of the end walls of the top frame; Fig. 8 is a detail perspective showing the means whereby the end walls 35 are hingedly connected with the bottom frame; and Fig. 9 is a fragmental elevation showing the means whereby one of the end walls is held engaged with the top frame; Fig. 10 is a detail perspective showing 40 the means whereby one of the end walls is prevented from swinging inwardly; Fig. 11 is a fragmental elevation showing a modified means for elevating the ends of the auxiliary top bar of one end wall.

45 In carrying out the invention there is provided a bottom frame denoted generally by the numeral 1, the same comprising side bars 2, end bars 3 and an intermediate longitudinal bar 4. The top frame 5 comprises 50 side bars 6, end bars 7, and an intermediate transverse bar 9. One end wall 10 comprises a top bar 11, a bottom bar 12 and side bars 14. The other end wall 15 comprises a top bar 16, a bottom bar 17, and end bars 18. 55 The end wall 15 further includes intermediate bars 19 connected with the top bar 16

and with the bottom bar 17. The intermediate bars 19 project above the top bar 16 for a purpose which will be set forth herein-after. The end wall 15 further includes an auxiliary top bar 20 secured intermediate its 60 ends as shown at 21 to those portions of the intermediate bars 19 which upstand above the top bar 16. The auxiliary top bar 20 is cut away in its lower edge and in its intermediate portion, between the bars 19 as indicated at 22. Through the portion 22 of the auxiliary top bar 20 extends a screw or bolt 23, the upper end of which is secured in the portion 22 of the auxiliary top bar 70 20. The lower end of the bolt 23 carries a wing nut 24 which bears against the lower edge of the top bar 16. Nuts 25 are seated in recesses 26 formed in the upper edge of the top bar 11 of the end wall 10. Engaged 75 through the nuts 25 are screws or bolts 27, the lower ends of the screws 27 being provided with turning heads 28. The upper ends of the screws 27 are adapted to seat in recesses 29 formed in the under face of one 80 end bar 7 of the top frame 5. The end walls 10 and 15 are connected with the bottom frame 1 by means of interengaging staples 30, or in any other manner, the construction being such that the end walls may be folded 85 inwardly, toward each other, to rest upon the bottom frame 1. Wire netting indicated at 31 is carried across the bottom frame 1 and across the top frame 5, the netting 31 surrounding the structure, to inclose the 90 same. Wire netting 31 is applied to the end walls 10 and 15, to complete the inclosure. Between the netting 31 and the bottom frame 1, oil cloth may be interposed as indicated at 1^a, although it is to be understood 95 that a closure of the bottom frame 1 may be effected in any other desired manner.

Flexible ties 33 of any desired form connect the end walls 10 and 15 with the bottom frame 1, as shown most clearly in Fig. 2, and 100 at this point it may be stated that the structure may be reinforced at any desired points. Outstanding from the side bars 6 of the top frame 5 are pins 34 adapted to be engaged by hooks 34^a pivoted to the side bars 2 of the 105 bottom frame 1.

There is an opening in that portion of the netting 31 which extends across the top frame 5. The periphery of this opening is 110 reinforced by a frame 35, the ends of which are secured to the intermediate transverse bar 9 of the top frame 5. A closure for the

above mentioned opening is provided, the closure including a U-shaped frame 36, located below the frame 35 and carrying netting 37. The ends of the lid frame 36 are curved as indicated at 38, these curved portions 38 being engaged with the netting 31 which is carried by the top frame 5, the curved portions 38 of the lid frame 36 being supported by the intermediate transverse bar 9 of the top frame 5, the extremities of the portions 38 resting upon the side bars 6 of the top frame 5, and being there secured by means of staples 39.

In practical operation, the end walls 10 and 15 may be folded inwardly and downwardly, toward each other, until they rest upon the bottom frame 1. Those portions of the netting 31 which lie between the bottom frame 1 and the top frame 5 may be creased longitudinally and folded inwardly toward the longitudinal center of the device, permitting the top frame 5 to be brought down upon the end walls 10 and 15, as shown in Figs. 4 and 5. The coop is thus disposed in small compass for shipping. The coop may be maintained in the folded position shown in Figs. 4 and 5 by engaging the hooks 34^a with the pins 34.

Netting as commonly constructed, consists of a plurality of diamond-shaped meshes. In employing wire netting of this type in a collapsible coop, considerable difficulty has been experienced heretofore by reason of the fact that the netting, having been bent a few times in the collapsing of the coop, soon becomes brittle and breaks. This difficulty I have overcome by placing the longer axes of the diamond-shaped meshes parallel to the line of folding, so that the twists uniting the meshes are not bent transversely when the netting is folded.

In order to open up the coop, the top frame 5 is lifted, and the walls 10 and 15 are raised until they engage beneath the ends of the top frame 5. By rotating the screws 27 through the medium of the turning heads 28, the upper ends of the screws will be advanced in the nuts 25 until the upper ends of the screws engage in the recesses 29 formed in the under face of the end bar 7 of the top frame 5. The foregoing operation applies peculiarly to that end wall which is denoted by the numeral 10.

In the case of the end wall 15, the wing nut 24 is manipulated, causing a depression of the weakened central portion 22 of the auxiliary top bar 20. The top bar 20 will fulcrum upon the connections 21, causing an elevation of the ends of the auxiliary top bar, the ends of the auxiliary top bar being pressed against the top frame 5. By the foregoing operation, the end wall 15 will be held in place securely.

As will be understood readily, the poultry may be placed within the coop by thrusting

them against the closure 36-37, the same opening inwardly to permit the entrance of the poultry. Owing to the manner in which the curved extremities 38 of the lid frame 36 are connected with the top frame 5, the lid 36-37 will be held closed, yieldably, it being understood that the lid frame 36 is a resilient structure.

Referring to Fig. 10, a means is shown whereby the end wall 15 may be prevented from swinging inwardly, this means comprising a latch 50 of any desired form, which may be secured to the side bar 6 of the top frame, to engage the auxiliary top bar 20 of the end wall 15, for the purpose specified. The latch 50 may be sprung readily out of engagement with the end wall 15, to permit the end wall to be swung into the coop when desired.

In Fig. 11 a modified means is shown for elevating the ends of the auxiliary top bar 20 of the end wall 15. In Fig. 11 a nut 52 is countersunk in, or otherwise secured to the auxiliary top bar 20, and a screw 53 is passed through the top bar 16, the screw being threaded into the nut 52. The upper end of the screw 53 is adapted to engage with the lower face of the end bar 7 of the top frame. When the screw 53 is brought into engagement with the end bar 7, the wall 15 will be held against swinging movement. Furthermore, when the screw 53 bears against the end bar 7, the intermediate portion of the auxiliary top bar 20 will be depressed, causing the ends of the bar 20 to be swung upwardly against the bar 7.

Having thus described the invention, what is claimed is:—

1. A coop comprising a top frame; a bottom frame; and netting constituting the sole connection between the frames; the netting being foldable to bring the frames together and consisting of diamond-shaped meshes, of unequal transverse dimensions, the longer dimensions of the meshes extending parallel to the frames, to facilitate the folding of the netting, and to avoid a transverse bending of the connections between the meshes.

2. A coop comprising a top frame; a bottom frame; an end wall hinged to the bottom frame; an auxiliary bar secured at spaced points to the end wall; and means connecting the end wall with the auxiliary bar, between said points, for depressing the intermediate portion of the bar and for elevating the ends of the bar to engage with the top frame.

3. A coop comprising opposed frames; an end wall bearing upon one frame; a bar having bearings at spaced points upon the end wall; and means connecting the end wall with the bar, between said points, for springing the intermediate portion of the bar transversely in one direction and for moving the ends of the bar in an opposite

direction with the bearing points as fulcrums, to cause the ends of the bar to engage with the other frame.

4. A coop comprising opposed frames; an end wall hinged to one frame; a bar having bearings at spaced points upon the end wall; manually operable means engaging the bar between said points to spring the intermediate portion of the bar transversely 10 in one direction and to move the ends of the

bar in an opposite direction with the bearing points as fulcrums, to cause the ends of the bar to engage with the other frame.

In testimony that I claim the foregoing as my own, I have hereto affixed my signature in the presence of two witnesses.

MINOR EUGENE TYNES.
